UNITED STATES PATENT OFFICE.

HARRY VISSERING, OF CHICAGO, ILLINOIS, ASSIGNOR TO HARRY VISSERING AND COMPANY, OF CHICAGO, ILLINOIS, A CORPORATION OF ILLINOIS.

LUBRICATOR.

1,119,902.

Specification of Letters Patent.

Patented Dec. 8, 1914.

Application filed January 14, 1910. Serial No. 538,016.

To all whom it may concern:

Be it known that I, HARRY VISSERING, a citizen of the United States, and a resident of Chicago, in the county of Cook and State of Illinois, have invented certain new and useful Improvements in Lubricators, of which the following is a specification.

My present invention relates to lubricator devices in general, and more particularly to oil cups which are employed to furnish an intermittent feed of oil to metallic bearing surfaces.

It has special reference to the provision of an improved type of cup of the character referred to by means of which oil is fed to the bearing only while the machine is in operation and in which such flow ceases upon stoppage of the machine. Devices so characterized are especially useful in connection with intermittently operated machinery, such as locomotive engines, automobiles, pumps, compressors and other machines in which guides, rocker boxes, stuffing boxes and non stationary bearings not only require continuous lubrication while moving but are otherwise not conveniently to be oiled by hand. Lubricating devices actuated by gravity alone are not satisfactory in such situations, since, when the machinery is inoperative the lubricators must also be made inoperative by closing a valve and if such shutting-off be neglected even occasionally or for a short time waste of oil is incurred.

The principal objects of my invention are the provision of an efficient and inexpensive device of the kind above specified, one which is to be cheaply manufactured, of low cost of maintenance, unlikely to become out of order or in need of repair and one which is uniform and certain in its operation; the provision of such a device having improved adjusting means whereby the oil feed may be regulated or controlled with much precision and nicety and adjustment made without the use of tools; the provision of improved means whereby the device may be quickly and conveniently opened for replenishing or for direct feed to the bearing where required, without disturbance of the normal feed or the adjustment thereof; the provision of improved means for holding the casing cover in place in order to prevent accidental displacement with possible consequent entrance of dust or foreign mat-

ter injurious to the device or its operation or to the bearing supplied thereby; together with such further objects as may be herein-after disclosed.

In the attainment of the objects above stated, as well as certain additional advantages which will be apparent to those who are skilled in the art to which my invention pertains, I have provided the constructions illustrated in the accompanying drawings, wherein—

Figure 1 is a vertical sectional view of a device embodying my invention; Fig. 2 is a horizontal sectional view taken on the line II—II of Fig. 1; Figs. 3, 4 and 5 are vertical sectional views of further devices embodying my invention; Fig. 6 is an elevational view of the device of Fig. 5 taken at a right angle thereto, and Fig. 7 is an under plan view taken on the line VIII—VIII of Fig. 5.

Referring now more particularly to Figs. 1 and 2 it will be noted that in carrying out my invention, I make use of a hollow body or shell 10, preferably of cast metal, here shown as provided with a shank 10^a by means of which it may be inserted in place. For a threefold purpose, viz.: to afford a seat for, and means for maintaining in place, the gravity actuated shut off device 11 and 80 to provide means for a direct feed of oil in the form in the floor of the shell an upstanding flange 11^a by which the inverted cup or bell shaped member 12, having a stem 13 with a passage 13^a is supported. The chamber 90 14 formed by the said flange 11^a and bell 12 and containing the ball 11 is provided with a sloping bottom 15 which communicates with the main oil reservoir 16 by means of a passage 17, formed in the floor 95 18 of the casing 10, and with the bearing by means of the passage 19 formed in the shank, 10^a.

To provide means for closely regulating the flow of oil from the main oil reservoir 100 16 through the passage 17 into the chamber 14, I employ a needle valve 21 seated at the point 22 where the passage 17 communicates with the reservoir 16. The said needle valve 21 is adjustable vertically by means of 105 its threaded engagement at 23 with a projecting web 24 formed across the top of the casing 10, the upper end 25 of the valve stem being provided with a thumb nut 26 fixed thereupon whereby it may be rotated.

To the end that the casing 10 may be kept tightly closed against the entrance of foreign matter and to prevent accidental change of adjustment of the needle valve without the use of a lock nut, set screw or the like, I employ the peculiar cover construction here shown, wherein it will be observed that adapted to coöperate with the orifice 27 having a beveled edge 28, is the cover plate 29 having a flange 30 oppositely beveled to contact therewith. To prevent tilting of the cover 29 it is provided at its extreme edge opposite the point indicated at 30, with a flat heel 31. The plate 29 is also provided with a housing 32 for a spring 33 the upper end of which seats in the thumb piece 26. The said spring 33 being inserted under compression exercises, as above suggested, the double function of exerting a downward pressure, holding the cover in position upon the casing and a lift on the stem 25 tending to prevent accidental change of adjustment of the valve 21.

It will be apparent upon reference to Fig. 1 that the vertical disposition of the valve stem 23 and its arrangement relatively to the cover plate 29 here shown is advantageous in that the valve stem is less likely to become broken or bent in service than if it were arranged at the side of the casing and that but a single spring (33) is required to maintain the valve and cover in position.

Referring now more particularly to Figs. 3 and 4, it will be seen that the devices here illustrated are similar to that of Fig. 1 save that the beveled surfaces 28^a and 30^a in Fig. 3 are disposed in directions opposite to those shown in Fig. 1, and that in Fig. 4 instead of surfaces beveled on one face only I employ doubly beveled surfaces 28^b and 30^b, combining, as it were, the interlocking features of Figs. 1 and 3.

On viewing Figs. 5, 6 and 7 it will be apparent that in this embodiment of my invention, instead of the beveled surfaces 28 and 30, and the heel 31, I provide a flat contact between the casing 10^c and cover 29^c and utilize downwardly projecting ears 34, 35 to prevent accidental displacement of the cover, and insert between the spring 33 and the bottom of the housing an antifriction bearing comprising balls 36 carried in a groove 37 and a bearing ring 38 upon which the spring 33 is supported, the cover being cut away as indicated at 38' to facilitate tipping thereof.

The operation of the device of Fig. 1 is as follows, (the operation of the other embodiments illustrated in Figs. 3, 4 and 5 be-

ing substantially the same,) viz.: The bearing is lubricated initially, (and thereafter when required) by lifting the cover 29 and turning it about the stem 25 as may be desired, and inserting the spout of the oil can in the passage 13^a. Oil then discharged 65 will flow into the chamber 14 and thence around the ball 11 into the discharge passage 19 to the bearing. The needle valve 21 having been previously adjusted for the desired volume of feed, the reservoir 16 is 70 filled and the cover 29 replaced. The passage 17 will then fill and as soon as the machine is put into operation the ball 11 will be thrown off its seat, allowing oil to flow into the chamber 14 until it reaches 75 the level of the top of the passage 19 when it will be discharged therethrough, thus allowing a continuous feed during the operation of the machine. As slight motion or jarring is sufficient to throw the ball 11 off 80 its seat, such ball opposes no obstacle to the flow of oil while the machine is in operation, but immediately upon the stoppage of the machine, the ball 11 reseats itself upon the orifice of the passage 17, cutting off all flow 85 of oil into the chamber 14 until the machine is again started.

Having thus described my invention and illustrated its use, what I claim as new and desire to secure by Letters Patent is the 90 following:

1. In a lubricator device, in combination, a reservoir casing, a chamber therein having a discharge outlet and a direct filling passage 13^a, a feed passage between said reservoir and chamber, means for varying the feed from said reservoir, a cover plate for said casing and chamber, and yieldingly resistant means for holding the said cover and feed varying means in adjusted position. 100

2. In a lubricator device, in combination, a reservoir casing, a chamber therein having a discharge outlet, and means for regulating the feed from said outlet, a feed passage between said reservoir and chamber, independent means for varying the feed from said reservoir, a cover plate for said casing and chamber, and yieldingly resistant means for holding said cover and feed varying means in adjusted position. 110

In testimony whereof I have hereunto signed my name in the presence of the two subscribed witnesses.

HARRY VISSERING.
